L. ERIKSON

LAMP SOCKET

Filed June 5, 1920

Inventor:

By Geo. K. Woodworth

atty.

UNITED STATES PATENT OFFICE.

LEONARD ERIKSON, OF MALDEN, MASSACHUSETTS.

LAMP SOCKET.

Application filed June 5, 1920. Serial No. 386,767.

To all whom it may concern:

Be it known that I, LEONARD ERIKSON, citizen of the United States, and a resident of Malden, in the county of Middlesex and 5 State of Massachusetts, have invented a new and useful Improvement in Lamp Sockets, of which the following is a specification.

My invention relates to incandescent lamp sockets and more especially in sockets adapted for use in show-case reflectors, and its 10 object, generally speaking, is to improve and simplify the construction of the same in the manner hereinafter set forth.

Specifically my object is to provide a two-part socket, the members of which may be clamped together and used for two lamps, or one member of which may be clamped to a base for use with a single lamp; to provide simple means for clamping the members 20 of the socket together; and to provide means for attaching the socket to the reflector.

With these objects in view my invention contemplates the use of two juxtaposed 25 blocks of insulating material, one or both of which have lamp-receiving chambers at their outer ends, and longitudinally aligned side recesses, a bridge in each side recess and means electrically and mechanically connecting one bridge with one or both of the 30 threaded metallic tubes placed in said chamber or chambers for receiving the lamps, and other means electrically and mechanically connecting the other bridge to one or both of the 35 spring contact members which make contact with the central terminal of the lamps, together with means, such as an elongated nut in a longitudinally extending recess in one of the socket members and longitudinally disposed screws passing through 40 said members and engaging said nut for clamping the socket members together, and means for securing the socket to the reflector or other support, such as a flat nut in a 45 lateral recess in one socket member and a screw threaded to said nut and having its head projecting above the socket.

My invention will be best understood by reference to the drawings which accompany 50 and form a part of this specification in which—

Figure 1 is a vertical longitudinal section of a double socket and show case reflector embodying my invention, said section being taken on the line 1—1 of Fig. 4. Fig. 2 is an end view. Figs. 3 and 4 are trans-

verse sections taken on the lines 3—3 and 4—4 respectively. Fig. 5 is a horizontal longitudinal section taken on the line 5—5. Fig. 6 is a vertical longitudinal section of a 60 single reflector embodying my invention, the section being taken on the line 6—6. Fig. 7 is an end view of the base end of the socket shown in Fig. 6. Fig. 8 is an end view of the chambered end of the socket shown in 65 Fig. 6.

In the particular drawings selected for more fully disclosing the principle of my invention 10 represents the top member of the reflector which as shown in my application Serial No. 386,768 filed simultaneously herewith is substantially horizontal when in use, 11 is the substantially vertical side member of said reflector and 12 the down-turned end portion in which the top member 70 terminates. A conduit having its base 13 resting on the reflector and the ends of its side members 14 resting on the reflector is suitably secured to the latter, as for example, by screws 14' which pass through the 75 reflector and are threaded to the base of the conduit in the manner disclosed in my application aforesaid, although it will be understood that any suitable means may be employed for this purpose. A saddle 15 having its top portion disposed opposite and 80 parallel to the base of the conduit and the ends of its side members resting on the latter so that a space is provided for electrical conductors between said base and 85 saddle, is clamped to the socket by the screw 16 the end of which is threaded to the flat nut 17 in a lateral recess in one of the 90 socket blocks, this arrangement resulting in the clamping of the conduit, the saddle and 95 the socket together. Electrical conductors 18, 19 are arranged in said conduit in the manner shown in Figs. 1, 3 and 4.

No claim is made herein to the combination of the reflector and socket and the construction whereby the terminals of the latter are connected to the conductors in said socket, as these features have been claimed in my application above referred to.

As shown in Fig. 1 my improved socket 105 consists of two blocks of insulating material 30, 31, the latter being provided with an axial recess and the former with a correspondingly shaped projection 32 fitting therein. The outer ends of each block receive 110 the threaded metallic tubes 33, 34 and the spring contact members 35, 36 respectively

which make contact in the usual manner with the cylindrical surface and the central terminal of an incandescent-lamp plug. For the purpose of mechanically connecting the 5 two blocks as well as electrically connecting the metallic tubes and spring clips respectively I employ metallic bridges located in the side recesses and screws which co-operate with the latter and with the respective blocks. The screw 37 passes through the block 30, its head engaging the tube 34 and its end being threaded to one end of the bridge 38 in the side recess 39 of the block 31, and the screw 40 passes through the 10 block 31, its head engaging the tube 33 and its end being threaded to the other end of the bridge 38. The screw 41 passes through the block 31, its head engaging the spring contact member 35 and its end being threaded to one end of the bridge 42 located in the side recess 43 of the block 30, and the screw 44 passes through the block 30, its head engaging the spring contact member 36 and its end being threaded to the other end 15 of the bridge 42.

While the arrangement above described joins the two sockets mechanically I prefer to strengthen the structure by means of an elongated nut 45 in a longitudinally extending recess of the block 31 and the longitudinally disposed screws 46 and 47 which pass through the lower portions of the blocks 30 and 31 respectively, the heads of said screws engaging the tubes 34, 33 respectively. 20 Conducting clips 48, 49 are soldered to the bridges 38, 42 respectively for receiving the conductors 18, 19 respectively.

In Fig. 6 the base 50 is provided with a side recess 51 in alignment with the recess 43 of the block 30 and receives the bridge 38 the ends of which are threaded to receive screws 37 and 40 which pass through said block and said base respectively. In this case the base and block are mechanically joined by the bridge 38 and its co-operating screws while the tube 34 is electrically connected to said bridge and the spring contact member 36 is electrically connected to the bridge 42 by the screw 44 as in the case of the double socket shown in Fig. 1. The base and block 30 are clamped together by means of the nut 45 and the screws 46 and 47'. 25

It will be apparent that the block 30 shown in Fig. 6 as clamped to a base to form a single socket is identical with the correspondingly numbered element shown in Fig. 1 as clamped to a similar block for the purpose of making a double socket.

Each block, and also the base 50 is provided with a projection 52 which fits into the slot 53 cut into the base of the conduit member 13 for properly positioning the socket with respect to the latter. The inner surfaces of said projections are beveled inwardly as shown at 54 to prevent a sharp

bend in the conductors as they pass from the conduit to the clips 48, 49, respectively.

After the conductors have been soldered to their clips the side recesses 39, 43 or 51, 43, as the case may be, are filled with insulating 70 cement.

It will be understood that while I have described one illustrative embodiment of my invention with some particularity, various modifications may be made therein without 75 departing from the scope of my invention as set forth in the appended claims.

I claim:

1. A show-case-reflector lamp-socket comprising in combination two blocks of insulating material, the juxtaposed inner ends of said blocks being provided respectively with an axial recess and a correspondingly shaped axial projection fitting into said recess, and with longitudinally extending aligned side recesses, the outer ends of each block having a chamber, a metallic tube for engaging the cylindrical surface of a lamp plug and a contact member for engaging the central terminal thereof in each said chamber, a bridge in each side recess, a screw passing through one block and having its head engaging the metallic tube in the chamber thereof and its end threaded to the bridge in the side recess of the other block, a screw passing through the second block and having its head engaging the metallic tube in the chamber thereof and its end threaded to said bridge, a screw passing through the first block and having its head engaging the contact member in the chamber thereof and its end threaded to the bridge in the side recess of said block, a screw passing through the second block and having its head engaging the contact member in the chamber thereof and its end threaded to the bridge in the side recess of the first block, and means for 80 85 90 95 100 105 110 115 120 125 130 clamping said blocks together.

2. A show-case-reflector lamp-socket comprising in combination two blocks of insulating material, the juxtaposed inner ends of said blocks being provided respectively with an axial recess and a correspondingly shaped axial projection fitting into said recess, and with longitudinally extending aligned side recesses, the outer ends of each block having a chamber, a metallic tube for engaging the cylindrical surface of a lamp plug and a contact member for engaging the central terminal thereof in each said chamber, a bridge in each side recess, a screw passing through one block and having its head engaging the metallic tube in the chamber thereof and its end threaded to the bridge in the side recess of the other block, a screw passing through the second block and having its head engaging the metallic tube in the chamber thereof and its end threaded to said bridge, a screw passing through the first block and having its head engaging the contact member in the chamber in the side recess of the second block, and means for clamping said blocks together.

chamber thereof and its end threaded to the bridge in the side recess of said block, a screw passing through the second block and having its head engaging the contact member in the chamber thereof and its end threaded to the bridge in the side recess of the first block, an elongated nut in a longitudinally extending recess in one block, and longitudinally disposed screws passing 10 through said blocks and engaging said nut.

3. A show-case-reflector lamp-socket comprising in combination two blocks of insulating material, the juxtaposed inner ends of said blocks being provided respectively with 15 an axial recess and a correspondingly shaped axial projection fitting into said recess, and with longitudinally extending aligned side recesses, the outer ends of each block having a chamber, a metallic tube for engaging the 20 cylindrical surface of a lamp plug and a contact member for engaging the central terminal thereof in each said chamber, a bridge in each side recess, a screw passing through one block and having its head engaging the 25 metallic tube in the chamber thereof and its

end threaded to the bridge in the side recess of the other block, a screw passing through the second block and having its head engaging the metallic tube in the chamber thereof and its end threaded to said bridge, a screw 30 passing through the first block and having its head engaging the contact member in the chamber thereof and its end threaded to the bridge in the side recess of said block, a screw passing through the second block and 35 having its head engaging the contact member in the chamber thereof and its end threaded to the bridge in the side recess of the first block, means for clamping said blocks together, a flat nut in a lateral recess 40 in one block below the side recess thereof, and a screw passing through said side recess and having its end threaded to said nut, the head of said screw projecting above said block for securing the socket to a support. 45

In testimony whereof, I have hereunto subscribed my name this 3rd day of June, 1920.

LEONARD ERIKSON.
